TOLL CHECKING SYSTEM

Benjamin Cooper, Jersey City, N. J.

Application August 3, 1940, Serial No. 350,261

6 Claims. (Cl. 235—92)

This invention relates to toll checking systems. The toll roads, bridges and tunnels of today are usually provided with a number of traffic lanes spreading out fanwise at the toll collection point. These lanes lead to a number of collection booths where the collectors are stationed. In many instances, several of these lanes are closed during the periods of little motor traffic and reopened when traffic again becomes heavy. During those hours when some of the lanes are closed the counting registers are left unguarded, making it a simple matter for any one to manipulate or tamper with the registers so that false counts are registered thereby.

It is, therefore, an object of this invention to provide in a counting register means for locking said register so that none of the push buttons in said register may be depressed.

In closing off some of the traffic lanes, or, in some instances where parking fields, provided with toll checking equipment, are closed, the authorities often desire a record to be made of the time when certain traffic lanes were shut off, or when parking fields were closed, and a record when they were again put into operation, as well as a record of the vehicle count during the periods of such operation.

It is, therefore, another object of this invention to provide in a register of the character described means for printing a record of the time and the vehicle count each time the register is locked and again when unlocked.

The practice today, in closing traffic lanes or parking fields, is to place barriers across the roadway barring the motorist from the particular traffic lane or parking field. This practice does not give the motorist much chance to maneuver his car before coming to the barrier. This last minute maneuvering of the motorist to get into an open traffic lane often leads to accidents. It would greatly aid the motorist were there some visual signal, such as a light, on top of the collection booth to indicate a particular booth and traffic lane open for toll collections.

It is, therefore, still a further object of this invention to provide in a register of the character described means for automatically actuating a signal in a lane upon unlocking the register for the lane, and automatically turning off the signal when said register is again locked.

Registers in use today are of various types, the most common of which is the shift bar type. This type of register uses a shift bar to actuate means for holding a depressed push button, or a switch actuated thereby, and for releasing a previously

depressed push button, or switch actuated by said previously depressed button. In the case of toll registers the switch actuated by the push button and held actuated by the shift bar means, usually 5 operates a classification indicator to show the type of vehicle last passing the toll station. When traffic is diverted from a particular lane and the register used in that lane is locked, this classification will still be shown on the indicator. Quite often a master switch is provided in toll checking systems to disconnect the system from a source of electrical energy. In such cases the classification indicator would be extinguished. However, when the master switch is again closed 10 to make the system operative, the classification last shown would again be flashed. It is therefore still another object of this invention to provide in a register of the character described means for releasing the last depressed push button and/or switch actuated by said button, when said device is locked.

Yet another object of this invention is to provide a strong, rugged, and compact device of the character described, which shall be easy to operate, relatively inexpensive to manufacture, positive in action, which shall have a large variety of applications, and yet be practical and efficient to a high degree in use.

Other objects of this invention will in part be 30 obvious and in part be hereinafter pointed out.

This invention accordingly consists in the features of construction, combinations of elements, and arrangement of parts which will be exemplified in the construction hereinafter described, 35 and of which the scope of this application will be indicated in the following claims.

In the accompanying drawings in which is shown one of the various possible illustrative embodiments of this invention,

Fig. 1 is a rear elevational view of a device embodying the invention;

Fig. 2 is a side elevational view of a device embodying the invention;

Fig. 3 is a side view of a device embodying the invention with portions broken away;

Fig. 4 is a cross-sectional view taken along the line 4—4 of Fig. 1;

Fig. 5 is a view similar to that shown in Fig. 4 showing the action of the push button upon being 50 depressed;

Fig. 6 is a wiring diagram showing the connection of the device in a toll checking system;

Fig. 7 is a front elevational view of a detail.

Referring now in detail to the drawings, 55 10 designates a device embodying the invention.

The device comprises a frame 11 having a base 13 and a front wall 12 extending upwardly therefrom. Extending rearwardly from the front wall 12 is the shoulder 12a bearing the removable cover 13a.

Projecting rearwardly from the front wall 12 is a vertical wall 17, Fig. 4, provided with a vertical row of equally spaced, horizontal, circular, recessed openings 18. Wall 17 is also formed with longitudinal openings 20 concentric and registering with the openings 18. Within each recessed opening 18 is a skirted portion 19 extending forwardly concentric with the opening 20. One side of the rear end of wall 17 is formed with a vertical notch 20a for the purposes hereinafter appearing. Extending rearwardly from wall 12 are two pairs of aligned bosses 14 disposed on the other side of wall 17 for the purposes hereinafter appearing.

Disposed within the openings 18 are the push buttons 21, 21a, 21b, etc., comprising plunger rods 22 and caps 23. Plunger rods 22 are disposed in the openings 20 and are connected to the caps 23 by means of collars 24 on said rods keyed to said caps as at 25. Within each recess opening 18 and about the portion 19 and rod 20 is a coil compression spring 26 one end of which contacts the bottom of recess 18 and the other end of which presses against a washer within the collar 24. Fixed to the rear end of each rod 20 is a contact piece 27 having the diametrically disposed, outward extending tongues 28 and 29.

Affixed to the side of wall 17, opposite to the side on which bosses 14 are located, as by screws 43, is a plate 44, perpendicular to the front wall 12. Fixed to plate 44 are pairs of switches 45, each comprising the normally open spring fingers 45a and 45b. There is one pair of switches for each push button in alignment with each of the openings 18. Means is provided for maintaining the pairs of switches open and to permit the switches associated with each push button to close when said push button is depressed.

To this end there is affixed to surface 20b of notch 20a in the wall 17, as by screws 30, a plate 31, perpendicular to front wall 12, and provided with a plurality of pairs of horizontally aligned screw threaded openings to which there are screwed headed studs 32. As shown in the drawings a pair of studs is disposed adjacent each switch 45. Plate 31 is also provided with the slotted openings 35 in alignment with said studs 32. Slidably mounted on each pair of studs 32 is a plate member 34, having slotted openings 33a and 33b to receive said studs. A portion of opening 33a overlaps a portion of opening 35 in said plate 31. Received within the openings thus provided through plate 31 and members 34 are tongues 29 of the contact pieces 27, for the purposes hereinafter appearing.

For purposes hereinafter described, each of the members 34 is provided with a dog 42, Fig. 2, having a vertical edge 42a and an inclined edge 42b. Fixed to an end of each of the members 34 and at perpendicular to the face thereof are two opposed laterally extending flanges 36 joined by rod 37. Rotatably mounted on said rod are insulated rollers 38. Affixed to the members 34 as by anchors 39, are coil tension springs 40 connecting said members to pins 41 on fixed plate 31.

Insulated rollers 38 are adapted to push back the spring fingers 45b when member 34 is in its normal position. Upon pressing the plunger, rollers 38 move away from fingers 45b permitting switches 45 to close. Release of the push button

will permit spring 40 to retract member 34 to normal switch opening position.

Pivoted to plate 31, Fig. 2, as by screws 46, are links 47 and 47a parallel thereto. Said links have pivoted at their rear ends, by screws 48, a shift bar 49 adapted to be moved parallel to the front wall 12. Affixed to the upper end of plate 31, as by screws 50, is a bracket 51. To the outer end of said bracket is fixed the coil tension spring 52, which is connected at its other end to link 47a, as at 53; said spring urging said link to rotate in a clockwise direction (Fig. 2) thereby tending to move shift bar 49 in an upward direction. Affixed to shift bar 49 and perpendicular to the face thereof are a plurality of aligned pins 54 abutting the inclined edges 42b of each of the dogs 42, limiting the upward movement of shift bar 49.

Pressing one of the push buttons 21, 21a, etc. will move rod 22 rearwardly against the action of spring 26 (Figs. 4 and 5). Tongue 29 engaging with opening 33b of member 34 will slide the said member rearwardly against the action of the spring 40. In moving member 34, the inclined edge 42b of the shoulder 42 will slide over pin 54, moving the shift bar downwardly against the action of spring 52. When pin 54 clears the edge 42b, spring 52 will move the shift bar upwardly, and the pin then engages the surface 42a of the dog 42. The release of pressure from the push button will allow the push button to return to its initial position. Member 34 will be retained in its rearmost position by pin 54 abutting the edge 42a of dog 42. The rearward movement of member 34 has carried with it the insulated roller 38, allowing the switches 45 to close.

To again open the switches 45, member 34 must be returned to its initial position. By pressing any one of the other push buttons, the shift bar 49 will be moved as hereinbefore set forth. When pin 54 clears the edge 42a of dog 42, spring 40 will return the previously held member 34 to its initial position, thereby causing the rollers 38 to contact the spring finger. Meanwhile, another member 34 is held by the shift bar, and another pair of switches 45 is allowed to close.

Mounted on the bosses 14, as by screws 56, is a flat plate 57, parallel with the front wall 12. Mounted on plate 57, as by screws 58, are a plurality of U-shaped members 59 aligned with the openings 18, each having parallel horizontal walls 60 and a vertical wall 61, about one half the length of the side walls. Fixed to the vertical wall 61 of each U-shaped member are a pair of switches 62, comprising the normally biased to closed position insulated spring fingers 62a and 62b, but maintained open when the device is not in operation, in the manner hereinafter appearing.

Means is provided to permit an open switch 62 to close when its push button is pressed, and to open again when pressure is released from said push button allowing said push button to return to its initial position.

To this end, there are affixed to the inner surfaces of the horizontal walls 60 of the U-shaped members 59, parallel plates 63 having edges 64. The edges 64 of said plates are cut away to form recessed edges 65. A shaft 66a is mounted through said plates 63 and the horizontal walls 60. To the outer surfaces of horizontal walls 60 and near the edges thereof are stud pins 66. Rotatably mounted on said stud pins is a toggle unit A, comprising a pair of aligned bell cranks 67, having arms 67a and 67b, and being interconnected by spacer rods 68 and 69. Rotatably mounted on spacer rod 69 are two insulated roll-

ers 70. Said rollers contact the spring fingers 62b of switches 62 holding the spring fingers apart.

Affixed to the inner surface of horizontal walls 60, are stud pins 71. Said stud pins 66, 71 are in vertical planes perpendicular to front wall 12. Rotatably mounted about stud pins 71 is a toggle unit B, comprising a pair of aligned bell cranks 72 having arms 72a and 72b, and being interconnected by means of spacer rods 73 and 74. Rod 74 is connected to rod 68 by a coil tension spring 75. Rods 73 and 66a are interconnected by a coil tension spring 76. A roller 70a is rotatably mounted on shaft 69a carried by arm 72a. Roller 70a is contacted by the tongue 28. Pressing a push button will thus rotate unit B in a counter-clockwise direction, looking at Fig. 4.

Toggle unit A is limited in its clockwise rotation about pin 66 by stops 79 at the rear edges of horizontal walls 60; and in its counter-clockwise direction by stops 80 at the rear edges of horizontal walls 60. Toggle unit B is limited in its clockwise rotation about pins 71 by the rear edges 64 of the plates 63, and in its counter-clockwise direction by the recessed edges 65 of plates 63.

By rotating toggle unit B in a counter-clockwise direction, spring 75 is rotated in a counter-clockwise direction about the rod 68. When spring 75 passes beyond a line interconnecting rods 68 and 74, a pulling force will be exerted on toggle unit A urging it to rotate in a clockwise direction. The rotation of toggle unit A will be halted when arms 67b engage the stops 79. The rotation of toggle unit B will be stopped when arms 72b engage the edges 65 of plates 63.

Upon releasing pressure from the push button 21, push button 21 will return to initial position. Spring 75 exerts a downward pull on toggle unit B, rotating the same in a clockwise direction until arms 72a again contact the upper edges 64 of plates 63. Spring 75 will be rotated by toggle unit B in a clockwise direction about rod 68. When spring 75 passes beyond a line interconnecting rods 68 and 74 force will be exerted on toggle unit A rotating it in a counter-clockwise direction until arms 67b contact the stops 80.

The spring fingers 62a and 62b are normally held out of engagement by the insulated roller 78 on toggle unit A. By rotation of toggle unit A in a clockwise direction, upon depressing a push button, spring fingers 62a and 62b are allowed to contact. The return of toggle unit A to its initial position will again interpose the insulated rollers, opening the contacts.

Affixed through the front wall 12, and near base 13, is a lock cylinder 16, extending beyond the rear surface of said front wall. Means is provided to prevent the depression of any of the push buttons upon rotation of the lock cylinder. To this end there is slidably mounted on the plate 31, and parallel thereto, a locking bar 85 slidably mounted in the guides 87 affixed to the said plate by screws 87a. Locking bar 85 is provided with a plurality of tongued portions 85a extending therefrom and spaced thereon so that each of the said portions engages a contact piece 27 when the bar is in its locked position. The locking bar is adapted to be shifted upwardly (Figs. 2 and 3) so that the tongued portions 85a will not limit the passage of the contact pieces 27, or pressing of the push buttons.

Pivoted at the lower end of locking bar 85 is a lever 88, having arms 88a and 88b, and pivoted

to plate 31 by screw 89. Arm 88b of said lever has at its outer end, the bearing opening 90.

Mounted on the rotatable barrel 16 as by screw 83, is a cam member 92 having an upward extending portion 94 provided with a bearing opening 95. Cam member 92 and arm 88b are interconnected by link 91 pivotally mounted in the bearing openings 95 and 90.

When key K is turned in lock cylinder 16 to unlock the device, said cylinder will rotate the cam member 92 in a clockwise direction through an angle of 90 degrees (Fig. 1). Link 91 will be pulled downwardly, rotating lever 88 about its pivot 89 in a clockwise direction. Lever 88 will in turn shift the locking bar 85 upwardly so that the tongued portions 85a no longer register with the contact pieces 27. The device is now in an operating condition and any of the push buttons may be depressed to actuate the respective switches.

To lock the device, the cylinder 16 is rotated in a counter-clockwise direction rotating the cam member 92 back to its initial position. Lever 88 is rotated in a counter-clockwise direction by link 91, thereby shifting the locking bar 85 downwardly so that tongued portions 85a again register with the contact pieces 27.

Means is further provided to release the last member 34 held by the action of the shift bar 49 automatically upon locking the device. To this end there is affixed to the lower end of shift bar 49, a pin 81a, perpendicular to the face thereof and so placed as to engage arm 88a of lever 88.

In locking the device, the rotation of lever 88 will engage the pin 81a and carry the shift bar 49 with it in a downward direction, against the action of the spring 52. Pin 54 on said shift bar will then release the dog 42 of the last held member 34 allowing said member to return to its initial position. In unlocking the device, lever 88 will permit the shift bar to return to its operating position by the action of its spring 52.

Fixed to the rear surface of front wall 12, as by screws 99, is a bracket 100. Fixed to said bracket and in alignment with cylinder 16 are switches 97 and 98 comprising the normally open spring fingers 97a and 97b, and 98a and 98b, respectively.

Means is provided to close the switch 97 momentarily each time the device is locked and again when unlocked, and to close the switch 98 and hold the same closed when the device is unlocked.

To this end cam member 92 is provided with a projecting portion 96 placed 135 degrees in a clockwise direction from the bearing opening 95. Cam member 92 is also provided with a notch 97c spaced 180 degrees from the said bearing opening. Pivoted to the rear surface of wall 12, as at 105a, is a lever 105 provided with an extension 106 bearing at its upper end the cam follower 107 registering with the notch 97c when the case is locked. Lever 105 is also provided with a downwardly extending insulated finger 108 contacting the spring finger 97a. Cam follower 107 is held in engagement with the periphery of the cam member 92 by spring 110 connected to lever 105 and to pin 109 in the rear surface of wall 12.

Pivoted to the rear surface of wall 12, as by screw 109a, is a bell crank 101 having arms 101a and 101b. Arm 101a bears at its outer end the cam follower 104, and arm 101b bears at its outer end the insulated button 103 contacting the spring finger 98a. Cam follower 104 is held in

engagement with the periphery of cam member 92 by action of spring 102 connected to arm 101b and to the rear surface of wall 12.

In unlocking the device, cam member 92 will be rotated through an angle of 90 degrees in a clockwise direction, looking at Fig. 1. Portion 96 will engage the cam follower 107 forcing lever 105 downwardly, closing the spring fingers 97a and 97b. As portion 96 passes beyond the cam follower 107, lever 105 will be moved upwardly by spring 110 permitting the contact of spring fingers 97a and 97b to be broken.

As cam member 92 rotates to its farthest position, cam follower 104 will drop into notch 97c. Arm 101b will be rotated in a clockwise direction thereby disengaging button 103 from spring finger 98a permitting the same to contact the spring finger 98b.

In locking the device, cam members 92 will be rotated in a counter-clockwise direction thereby rotating bell crank 101 in a counter-clockwise direction. Button 103 will again contact spring finger 98a breaking the contact of the said spring finger with spring finger 98b. Portion 96 on said member will again engage the cam follower 107 rotating the lever in a counter-clockwise direction thereby closing the spring fingers 97a and 97b. Upon the return of cam member 92 to its initial position, cam follower 107 will again engage notch 97c permitting switch 97 to open.

Referring now to Fig. 6, C designates an electrical circuit including electromagnetic counters M, M1, M2, and M3, there being one for each push button. Said counters have coils 125, 126, 127 and 128, respectively. One end of each of the said coils is connected to plus power supply. The other end of coil 125 is connected by wire 125a to switch arm 62b of switch 62 associated with push button 21. Coil 126 is connected by wire 126a to switch arm 62b of switch 62 associated with push button 21a. Coil 127 is connected by wire 127a to switch arm 62b of the switch 62 associated with push button 21b. Coil 128 is connected by wire 128a to switch arm 62b of the switch 62 associated with push button 21c. Associated with the electromagnetic counters M, M1, M2, and M3 are aligned digit wheels D, D1, D2, and D3, said digit wheels being adapted to be advanced one digit for each impulse received by its electromagnet. The switch arms 62a of switches 62 of the device are all connected to minus power supply.

Said circuit further includes classification indicators, such as visual signals L, L1, L2 and L3, there being one for each push button. Signal L is connected to plus power supply and by wire 130 to switch arm 45b of switch 45 associated with push button 21. Signal L1 is connected to plus power supply and by wire 131 to switch arm 45b of switch 45 associated with push button 21a. Signal L2 is connected to plus power supply and by wire 132 to switch arm 45b of switch 45 associated with push button 21b. Signal L3 is connected to plus power supply and by wire 133 to switch arm 45b of switch 45 associated with push button 21c. Switch arms 45a of said device are all connected to minus power supply.

Pressing push button 21 will close switches 45 and 62 in the manner previously described. Closing switch 45 will complete a circuit for signal L, the circuit being through switch 45, wire 130 and signal L. Signal L will remain actuated as long as switch 45 remains closed. Closing switch 62 completes a circuit through coil 125 of electromagnetic counter M, the cir-

cuit being through switch 62, wire 125a and coil 125. Electromagnetic counter M thereby receives a pulse to advance its digit wheel one figure. The circuit for the electromagnetic counter M is again opened by switch 62 opening in the manner previously described.

By depressing another push button similar circuits will be completed for the other electromagnetic counters, and for the other classification signals. Each signal will remain actuated until another push button is depressed or when member 34 is released to return to its initial position when the device is locked in the manner heretofore described.

15 A second circuit C1 is provided including a printing solenoid S to print against the counter wheels as in applicant's U. S. Patent No. 2,293,934, issued August 25, 1942. A timer T also is provided having time and date wheels 134 in alignment with the digit wheels D, D1, D2, and D3.

20 Solenoid S is provided with the coil 135, one end of which is connected to minus power supply, and the other end by wire 135a to switch arm 97b in said device. The armature of said solenoid S is provided with a printing platen 137 contacting the digit wheels D, D1, D2 and D3, and also the time and date wheels 134. Switch arm 97a is connected to plus power supply.

25 In closing and opening the switch 97 in the manner hereinbefore described a circuit will be completed energizing the solenoid S, the circuit being through switch 97, wire 135a and coil 135. Platen 137 will be raised, striking the said digit wheels, paper and ribbon being interposed, in the well known manner, making a record of the time and vehicle count. Opening switch 97 will de-energize the solenoid S thereby allowing platen 137 to return to its initial position.

30 The circuit C1 is further provided with the visual signals S and S1, the former to indicate that the device 10 is in operation, and the latter to indicate that said device is locked and not in operation. Said signals are actuated by the switch 98 in said device. To operate said signals 35 there is provided an electromagnet 140 having a coil 141, said coil being connected at one end to minus power supply, and its other end by wire 141a to switch arm 98b. Associated with said electromagnet and adapted to be moved thereby upon energization, is the movable switch arm 143. The movable switch arm normally engages the contact 144, but is adapted to be moved out of engagement with contact 144, and into engagement with contact 145.

40 45 50 55 Contact 144 is connected by wire 144a through signal S1 to plus power supply, and contact 145 is connected by wire 145a through signal S to plus power supply. Switch arm 143 is connected to minus power supply.

60 65 70 75 By closing switch 98 in the manner heretofore described, electromagnet 140 will be energized by the circuit through said switch, wire 141a and coil 141. Switch arm 143 will move out of engagement with contact 144 and into engagement with contact 145. Signal S will then be actuated, the circuit being through switch arm 143, contact 145, wire 145a. In opening switch 98 of the device, electromagnet 140 becomes de-energized and switch arm 143 again engages the contact 144. Signal S is then actuated by the circuit through switch arm 143, contact 144, wire 144a.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth, or shown in the accompanying drawings is to be interpreted as illustrative and not in a limiting sense.

Having thus described my invention, I claim as new and desire to secure by Letters Patent:

1. In combination, a frame, a plurality of 10 pressible plungers mounted thereon, means for returning a pressed plunger to initial position, a key controlled rotary means mounted in said frame, a member mounted on said rotary means and adapted to be rotated therewith, a lever pivoted to said frame, a link, pivotally connected at one end to said member and pivotally connected at its other end to said lever, and a locking bar mounted on said frame and adapted to be moved to lock said plungers against movement, said locking bar being pivotally connected to said lever and adapted to be moved into locking position upon rotation of said rotary means, a switch for each plunger, means for actuating each switch upon pressing its plunger, means to hold each actuated switch in actuated condition upon release of its plunger, means to release a switch actuated by its plunger upon pressing another plunger, and means connected to said lever to release the last actuated switch without pressing another plunger.

2. In combination, a frame, a plurality of pressible plungers mounted thereon, a switch associated with each plunger, a switch actuating member associated with each plunger and its switch mounted on said frame and adapted to be moved upon pressing its plunger to actuate its switch, means to return a pressed plunger to initial position, a shift bar mounted on said frame, means on said shift bar to hold a switch actuating member in switch actuating position after the return of its plunger to initial position and to release a switch actuating member previously held by subsequently pressing another plunger, a key controlled rotary member mounted in said frame, a member mounted on said rotary means and adapted to be rotated therewith, a lever pivoted to said frame, a link pivotally connected at one end to said member and pivotally connected at its other end to said lever, a locking bar mounted on said frame and adapted to be moved to lock said plungers against movement, said locking bar being pivotally connected to said lever and adapted to be moved into locking position upon rotation of said rotary means, and means on said shift bar to engage said lever upon rotation thereof to release the last held switch actuating member.

3. In combination, a plurality of pressible keys, a member associated with each key and adapted to be moved thereby, upon pressing said key, a shift bar having means to engage each member moved by its key, for retaining said member in moved position, each of said members having means to shift the shift bar as said member is moved by its key to release any member previously retained in moved condition by said shift bar, a lock bar having a plurality of lock means adapted in one position of the lock bar to lie in the paths of said keys to prevent pressing of said keys, and in another position of said lock bar being clear of said keys, to permit pressing of said keys, means

5 to move said lock bar from clear position to locking position, and means on said lock bar moving means to shift the shift bar to release the last retained member without pressing of any key.

4. In combination, a plurality of pressible keys, means associated with each key to bias the same to normal position after said key has been pressed, a member associated with each key and adapted to be moved thereby upon pressing said key, means to urge each moved member to normal position upon movement of its key back to normal position, shift means to engage any of said members moved by its key, for retaining said member in moved position while its key returns to normal position, each member having means to shift said shift means as said member is moved by its key, to release any other member previously retained in moved position by said shift means, to permit said member to be moved back to normal position, retain means having means, in one position thereof, to lie in the paths of said keys to retain said keys against pressing, and in another position thereof being clear of said keys to permit pressing of said keys, means to move said retaining means from clear position to retaining position, said means for moving the retaining means having means to also shift the shift means to release the last retained member without pressing of any key, whereby to permit movement of the last moved member back to its normal position and simultaneously retain all of the keys against further pressing, and means to lock said moving means in actuated position to lock said retaining means in retaining position.

5. In a key board, in combination, a plurality of pressible plungers, a switch for each plunger, means for actuating each switch upon pressing its plunger, means for returning a pressed plunger to initial position, means for retaining all of said plungers against pressing in the actuated position of said retaining means, said plungers being free of said retaining means in the normal position of said retaining means, means to actuate 45 said retaining means, means for holding a switch actuated upon return of its plunger to initial position, means to release the last actuated switch upon pressing another plunger, means to release the last actuated switch upon operating said 50 actuating means, and means to lock said actuating means in operative position to lock said retaining means in retaining position.

6. In a key board, in combination, a plurality of pressible plungers, a switch associated with 55 each plunger, a switch actuating member associated with each switch and its plunger and adapted to be moved upon pressing its plunger to actuate its switch, means to return a pressed plunger to initial position, means to hold the switch actuating member in switch actuating position after the return of its plunger to initial position and to release a switch actuating member previously held in switch actuating position upon subsequently pressing another plunger, a key 60 cylinder, a member movable by said key cylinder, means controlled by said member for locking all of said plungers against movement, and means actuatable by said member when it operates said locking means to simultaneously release the last held switch actuating member.

BENJAMIN COOPER.
